US0D1109794S

(12) **United States Design Patent** (10) Patent No.: **US D1,109,794 S**
(45) Date of Patent: ** Jan. 20, 2026

(54) **GOGGLES WITH REMOVABLE NOSEPIECE AND BI-MATERIAL ARMS**

(71) Applicant: **BOLLE PROTECTION**, Villeurbanne (FR)

(72) Inventor: **Cédric Peillon**, Saint-Romain-en-Jarez (FR)

(**) Term: **15 Years**

(21) Appl. No.: **35/521,689**

(22) Filed: **Jun. 17, 2024**

(80) **Hague Agreement Data**

Int. Filing Date: **Jun. 17, 2024**

Int. Reg. No.: **DM/238292**

Int. Reg. Date: **Jun. 17, 2024**

Int. Reg. Pub. Date: **Jul. 19, 2024**

Primary Examiner — Sanjeev Paul

(57) **CLAIM**

The ornamental design for goggles with removable nosepiece and bi-material arms as shown and described.

DESCRIPTION

1. Goggles with removable nosepiece and bi-material arms

1.1 : Perspective

1.2 : Perspective

1.3 : Back

1.4 : Front

1.5 : Bottom

1.6 : Top

1.7 : Right

1.8 : Left

1.1 Perspective back view; 1.2 Perspective front view; 1.3 Back view; 1.4 Front view; 1.5 Bottom view; 1.6 Top view; 1.7 Right side view; 1.8 Left side view.

The gray-toned shading is intended to depict a different material and forms a part of the claimed design.

1 Claim, 8 Drawing Sheets
